UNITED STATES PATENT OFFICE.

GREGORY C. DAVISON, OF NEW LONDON, CONNECTICUT, ASSIGNOR TO ELECTRIC BOAT COMPANY, OF NEW YORK, N. Y., A CORPORATION OF NEW JERSEY.

IGNITION APPARATUS FOR POWER-GENERATING SYSTEMS.

1,079,748.

Specification of Letters Patent.

Patented Nov. 25, 1913.

Original application filed November 4, 1910, Serial No. 590,627. Divided and this application filed July 22, 1912. Serial No. 710,786.

To all whom it may concern:

Be it known that I, GREGORY C. DAVISON, a citizen of the United States, residing at New London, county of New London, State 5 of Connecticut, have invented certain new and useful Improvements in Ignition Apparatus for Power-Generating Systems; and I do hereby declare the following to be a full, clear, and exact description of the invention, such as will enable others skilled in the art to which it appertains to make and use the same.

The present invention relates to an ignition attachment to be associated with any 15 chamber or the like into which it is desired to project an ignition blast of flame.

The device is particularly adapted for use in connection with the ignition of the combustible mixture in the generator for automobile torpedoes disclosed in my United States Patent No. 1,036,081 of August 21, 1912, granted on application Ser. No. 590,627, filed November 4, 1910, and of which this application is a division.

The particular object of the invention is to provide such an attachment which constitutes a self-contained unit capable of being operatively attached to or associated with the generating chamber, and provided 25 with mechanism for igniting the fuse, which mechanism is preferably actuated by means of a fluid. To this end, it comprises essentially a casing containing a chamber adapted to receive a combustible fuse, from which 35 chamber an outlet duct leads through the casing for the purpose of directing the products of combustion of the fuse into the chamber to which the ignition device is attached. The fuse-receiving chamber has an open

40 mouth in which a fuse-carrying plug is seated, and the casing supports a trigger arranged to co-act with a firing pin carried by the plug; said trigger being actuated by suitable means, preferably a diaphragm 45 within a diaphragm chamber forming part of the casing and having pressure connections.

In the drawing—Figure 1 is a vertical section of the improved ignition attachment 50 constructed in accordance with the invention; Fig. 2 is a sectional plan on the line 3—3 of Fig. 1; and Fig. 3 is a sectional plan on the line 4—4 of Fig. 1.

This ignition mechanism comprises a cas-

ing *l*, having a lateral extension *l'* screwed 55 to the wall of the generating chamber *f*, the extension containing an open duct through which communication is established between the interior of the casing *l* and the combustible mixture in the generating chamber. 60 This casing *l* constitutes a receptacle for the fuse case *m*, which is screwed into the plug *n*, fitting in the enlarged upper end of the casing *l*, and adapted to be forced onto the seat at the lower end of the enlarged portion by means of the surrounding screw 65 lower nut *p*. The plug *n* constitutes a guide sleeve for the firing pin *q*, which is urged to the firing position by the coiled spring *r*, confined between the trigger disk *v'*, and the screw cap *w'*, which screws onto the upper end of the plug *n*.

The trigger disk *v'* has a projection *v*², extending into a slot in the side of plug *n*, and engaging the trigger *z* pivoted at *z'* in 75 the wall of the laterally extending chamber *l'*, which extends from the fuse receptacle *l*. This chamber contains a flexible diaphragm *a'*, seated on a shoulder in the casing *l'*, and carrying a plunger *b'*, to which the end of 80 the trigger *z* is connected, the spring *c'* being provided to force the diaphragm outwardly. The diaphragm is held in position by the screw cap *d'*, which has a pressure-admission orifice *e'*, connected by the pressure pipe *f'* to a part of the pressure system 85 which supplies the fuel.

The parts are prepared for the firing in the following manner: The fuse *m*, being provided with a blank cartridge *m'* at 90 its upper end, is screwed into the plug *n*. The plug is then inserted in the casing *l*, and turned until the trigger *z* is projected into the slot, whereupon the follower nut *p* is screwed down. This forces the plug 95 against its seat and at the same time cocks the firing pin, the firing spring *r*, being then inserted and the cap *w'* screwed into place. The parts are then ready for firing by the pressure of the fuel acting against the diaphragm *a'*.

A firing attachment constructed in accordance with my invention has the great advantage that it projects a violent stream of the products of combustion of the fuse into the generating chamber, and the fuse itself is not exposed to the rush of air or other fluid which may be passing through the 100 105

chamber, and which would have a tendency to extinguish a fuse exposed to it. Furthermore, the device lends itself readily to adjustment, for the purpose of regulating the precise instant at which the igniter is fired with a given pressure of trigger actuating fluid, because the diaphragm spring may easily be removed and replaced by one of different strength.

10 What I claim is:

1. A firing attachment for the purpose described, comprising a casing, having a fuse-receiving chamber with an outlet duct for the product of combustion of the fuse, 15 the portion of the casing surrounding said duct being adapted for attachment to a chamber into which it is desired to project an ignition flame, a fuse-carrying plug projecting into said chamber, and means for 20 igniting the fuse.

2. A firing attachment for the purpose described, comprising a casing having an open-mouthed fuse-receiving chamber with a lateral outlet duct for the products of combustion 25 of the fuse, the portion of the casing surrounding said duct being adapted for attachment to a chamber into which it is desired to project an ignition flame, a fuse-carrying plug seated in the mouth of said 30 chamber, and means for igniting the fuse.

3. A firing attachment for the purpose described, comprising a casing containing a fuse-receiving chamber with a lateral outlet duct for the products of combustion of the 35 fuse, the portion of the casing surrounding said duct being adapted for connection to a chamber into which it is desired to project an ignition flame, a slotted plug projecting into said chamber and carrying a fuse and

firing pin, a pivoted trigger on said casing 40 extending through the slot in the plug into the path of the firing pin, a diaphragm-chamber on the casing, a diaphragm and diaphragm spring therein, the diaphragm being connected to the trigger, and pressure 45 connections to the diaphragm chamber.

4. A firing attachment for the purpose described, comprising a casing containing a fuse-receiving chamber with a lateral outlet duct for the products of combustion of the 50 fuse, the portion of the casing surrounding said duct being adapted for connection to a chamber into which it is desired to project an ignition flame, a slotted plug projecting into said chamber and carrying a fuse and 55 firing pin, a pivoted trigger on said casing extending through the slot in the plug into the path of the firing pin, a diaphragm-chamber on the casing, a diaphragm and diaphragm spring therein, the diaphragm 60 being connected to the trigger, and pressure connections to the diaphragm chamber, the said diaphragm chamber having a removable cap.

5. Firing pin releasing mechanism for the 65 purpose described, comprising a pivoted trigger, a diaphragm casing containing a diaphragm and plunger connected to said trigger, a spring surrounding said plunger and pressing the diaphragm outwardly, and 70 a removable cap closing the end of said casing.

In testimony whereof I affix my signature, in presence of two witnesses.

GREGORY C. DAVISON.
